UNITED STATES PATENT OFFICE.

LIDA A. TARRING, OF BALTIMORE, MARYLAND,

EXTENSION JOINT OR SPLICE.

SPECIFICATION forming part of Letters Patent No. 407,795, dated July 30, 1889.

Application filed July 16, 1888. Serial No. 280,050. (No model.)

To all whom it may concern:

Be it known that I, LIDA A. TARRING, a citizen of the United States, residing at Baltimore, in the State of Maryland, have invented 5 certain new and useful Improvements in Extension Joints or Splices; and I do hereby declare the following to be a full, clear, and exact description of the invention, such as will enable others skilled in the art to which it

appertains to make and use the same.

My present invention is an improvement in extension-couplings for broom-handles or the handles of other articles of household use to be used when a more than ordinary reach is 15 required in sweeping, brushing, or other cleaning.

The coupling is formed of a piece of sheet metal, preferably, with parts stamped or cut out to form openings, which, when the piece so 20 formed is doubled upon itself longitudinally in the form of a broken cylinder and riveted together, it is only necessary to introduce thumb or clamping screws into the bands to render the coupling complete for use.

25 The coupling is well adapted for the extension of a broom or brush, and may be used also to hold a duster-brush, the handle of which may be run at right angles to the broom-handle through openings provided for it and there 30 clamped to place, so that the smallest corners may be reached and freed from dust, cobwebs, &c.

In the drawings illustrating my invention, Figure 1 is a view showing the blank from 35 which the coupling is formed. Fig. 2 is an elevation showing the coupling used as an extension-piece for a broom. Fig. 3 is a view showing how the duster may be held in the coupling.

40 Similar reference-letters indicate like parts in all of the figures.

Referring to the drawings, A is the blank provided with rectangular openings *a b* and circular openings *c d*.

45 *e* and *f* are the parts of the coupling which lap the one over the other, when the cut-out blank is doubled over in cylindrical form.

g, h, and *i* are cylindrical loops, the former and latter of which are provided with screw-threaded openings for thumb-screws *k l*. The 50 loop *h* covers the line which divides the two spliced sticks. The loop *g* is provided with opposite openings *c d*, through which is passed the handle of a feather-duster, which may be clamped to a fixed position by means of the 55 thumb-screw *k*.

In the use of the coupling, when the handle of a broom for any purpose needs to be extended, said handle is placed through loop *i* and to the middle of the loop *h*, and there 60 clamped by the thumb-screw *l*. A stick of the desired length is now placed in the opposite direction through the loop *g* and moved toward the broom-handle until it meets said handle's end, when the said stick is clamped 65 to place by the thumb-screw *k*.

When the feather-duster or brush is used, the handle of the broom, or a stick representing it, is clamped by the thumb-screw *l*, and the handle of the said duster or brush is introduced into openings *c d* and there clamped by the thumb-screw *k*.

70 My device is simple in construction, and, though preferably made of sheet metal, is strong, efficient, and durable.

75 Having thus described my invention, what I claim as new, and desire to secure by Letters Patent, is—

The coupling, as a new article of manufacture, formed from a cylinder and having three 80 cylindrical bands, one of which is pierced with two opposite openings, and the other two provided with screw-threaded openings and thumb-screws, substantially as and for the purpose set forth.

85 In testimony whereof I affix my signature in presence of two witnesses. .

LIDA A. TARRING.
